UNITED STATES PATENT OFFICE.

PETER W. CHMIELOWSKI, OF CHICAGO, ILLINOIS.

TABLE.

1,375,488.

Specification of Letters Patent. Patented Apr. 19, 1921.

Application filed November 13, 1920. Serial No. 423,871.

To all whom it may concern:

Be it known that I, PETER W. CHMIELOWSKI, a subject of the Republic of Poland, residing at Chicago, in the county of Cook 5 and State of Illinois, have invented new and useful Improvements in Tables, of which the following is a specification.

This invention relates to improvements in tables and consists in the matters herein-10 after described and more particularly pointed out in the appended claims.

In the accompanying drawings—

Figure 1 is a top plan view of a game 15 table embodying the features of my invention;

Fig. 2 is a side elevational view of said table, the game board being shown in raised position above the table;

Fig. 3 is a bottom plan view of the table; 20 Fig. 4 is an enlarged vertical sectional view taken on line 4—4 of Fig. 3, the parts being shown in their normal positions;

Fig. 5 is a similar sectional view of said 25 parts, but shown in the positions they occupy when the game board is raised above the table;

Fig. 6 is an enlarged vertical sectional view taken on line 6—6 of Fig. 3, the parts being in their normal positions; and

Fig. 7 is a perspective view of the de-30 pressible plate on which the game board is mounted.

In the drawings, 1 indicates a table of that type having a flat top 2 and four legs 35 3, one at each of the four corners of the table; the legs being connected by side and end brace rails 4, 5 extending between the legs and around the table directly beneath the under side of the top.

To provide said table with a game board 40 construction of my invention, I cut a square hole or opening 6 in the top 2 adjacent one of the end rails 5, just inside of it, and make the opening of a size to receive a square board 7, which when in the opening fits and closes the same. The board 45 7 is flat and one face has a checkered surface like a checker-board so that a game of checkers or chess or other game using a checker board may be played on the table 50 by the use of the board 7. The opposite flat face of the board 7 is given a finish like that of the top of the table, so that when the board is reversed and covers the 55 opening 6, the board will appear to be a

part of the top 2 and the table may be used for dining, reading, or any other like purpose.

Secured to the under side of the top 2 about the opening 6 is an open box like 60 frame 8 having an out-turned flange 9 about its upper margin for fastening the frame to the top 2, and an inturned flange 10 about its bottom margin to strengthen the frame and to act as a stop flange for the depressible plate 11 in the frame. This plate 11 is square, like the frame, and is slidably mounted on an upright post 12 arranged within the frame and centrally thereof. This post, as shown, is square and extends 70 through a square hole 13 in the plate 11, as indicated in Fig. 7. This prevents the plate 11 from turning on the post. The latter has its upper end slightly below the upper surface of the top 2, and is secured 75 at its lower end to a cross-bar 14 extending across the frame 8 at its lower edge and secured thereto.

Between the plate 11 and cross-bar 14 is an expansion spring 15 coiled widely and 80 loosely about the post 12. This spring serves, when released, to raise the plate 11 upward, the upward movement of the plate being limited by a cross-pin 16 at the upper end of the post. To the under side of 85 the plate 11 is secured a collar 17 extending about the post 12. Depending from this collar is a fixed locking member 18, which, when the plate 11 is fully depressed, passes through an aperture 19 in the cross-bar 14 90 and hooks over the inner end of a latch bar or rod 20 slidably mounted on the cross-plate 14 and having its outer end connected with the lower end of a lever 21 pivoted between its ends to a bracket 22 secured to 95 the inner side of one of the side rails 4, as shown in Fig. 6. To the upper end of the lever is secured a rod 23 extending through the side rail 4 and having a push button 24 on its outer end. This button when 100 pushed inward moves the rod 20 out of locked engagement with the locking member 18, thereby releasing the spring 15 and enabling the plate 11 to be projected upward carrying therewith the board 7. A spring 105 25 returns the rod 20 back in position to lock with the member 18 when the plate 11 is depressed. The button 24 is located in a recess 26 in the rail 4 and lies substantially flush with the outer surface of the 110

rail so as to have no parts projecting outside of the rail to be readily seen or mar the appearance thereof.

Projecting above the plate 11 at opposite sides thereof are two arms 27, 27. Between these the board 7 is pivotally mounted. The board has trunnion pins 28, 28 to engage in apertures at the upper ends of said arms. These arms are slightly resilient and may be readily spread apart to release the board 7 and permit it being reversed to bring either of its two flat surfaces, one plain and the other checkered, to view. A leaf spring 29 is secured to the plate 11 under the board 7 and bears against the same in a manner to swing the board upward about its pivot pins when the board is carried above the table, as shown in Figs. 2 and 5. The backward swinging movement of the board is limited by a stop member 30, which as shown is secured to the plate 11, and allows the board to stand in open position, as shown. To hold the board in horizontal position when flush with the table top, I provide a spring 31 secured to an upright strip 32. The upper end of this latch 31 is turned in to enter a recess 33 in the associated edge of the board, as shown in Fig. 4. The strip 32 is secured to the plate 11 and acts as a stop when the board is swung down into horizontal position, and also to prevent the recess 33 from being carried downward past the upper end of the latch 31. This latch 31 is moved into locked engagement with the board 7 when it is forced down into the table opening 6 for closing the same.

The game pieces (not shown) when not in use are kept on the plate 11, and when the latter is depressed and the board 7 held flush with the table top, the game pieces and other articles on the plate 11 are out of view and confined in the compartment formed by the parts described. To use the board to play a game, the button 24 is pressed inward, releasing the compressed spring 15, and the plate 11 brought up substantially flush with the table top. The board 7 is automatically swung open, so that it will not interfere with reaching the game pieces on the plate 11. After these are taken out, the board 7 is swung down and depressed to close the opening 6, and the latch devices hold the parts in that position to enable a game to be played on the board. After the playing has been finished, the board 7 is again raised and the game pieces put back on the plate 11, whereupon the parts are again depressed and held locked as before. If desired, the board may be reversed for the purposes mentioned.

While I have shown and described herein in detail a construction of my invention, it is of course to be understood that the details of construction and arrangement of parts may be variously changed and modified

without departing from the spirit and scope of my invention.

I claim as my invention:

1. The combination with a table having a flat top with an opening within the margin thereof, of a flat board to fit in and close said opening, said board having a game surface on one side and a plain surface finished like the table top on the other side, depressible means for supporting said board and raising the same above the table top, latch mechanism for holding the board depressed flush with said top, means on the table for operating said latch mechanism for releasing said board, and means detachably connecting said board with said depressible means in a manner permitting said board to be reversed.

2. The combination with a table having a flat top with an opening within the margin thereof, of a game board to fit in and close said opening and be flush with said top, a frame secured to said table beneath said top and surrounding said opening, a vertically depressible plate slidably mounted in said frame, means supporting said board above said plate, a spring for raising said plate and carrying the board above said top, a latch mechanism for holding said plate depressed with said board flush with said top, and means on the table for operating said latch mechanism for releasing said plate.

3. The combination with a table having a flat top with an opening within the margin thereof, of a game board to fit in and close said opening and be flush with said top, a frame secured to said table beneath said top and surrounding said opening, an upright post in the center of said frame and secured thereto, a vertically depressible plate slidably mounted on said post, means supporting said board above said plate, a spring surrounding said post beneath said plate for raising the same and carrying the board above said top, a latch mechanism for holding said plate depressed with said board flush with said top, and a push button mounted on the table and connected with said latch mechanism so that the same may be operated for releasing said plate.

4. The combination with a table having a flat top with an opening within the margin thereof, of a game board to fit in and close said opening and be flush with said top, a frame secured to said table beneath said top and surrounding said opening, a vertically depressible plate slidably mounted in said frame, means supporting said board above said plate, a spring for raising said plate and carrying the board above said top, a latch mechanism for holding said plate depressed with said board flush with said top, said latch mechanism comprising two locking members, one carried by said plate and the other mounted on said frame and adapted to snap into locking engagement when

said plate is fully depressed, and means on the table for operating said latch mechanism for releasing said plate.

5. The combination with a table having a flat top with an opening within the margin thereof, of a game board to fit in and close said opening and be flush with said top, a frame secured to said table beneath said top and surrounding said opening, a vertically 10 depressible plate slidably mounted in said frame, means supporting said board above said plate, a spring for raising said plate and carrying the board above said top, a latch mechanism for holding said plate depressed with said board flush with said top, said latch mechanism comprising two locking members, one in the form of a hook carried by said plate, and the other in the 15 form of a spring pressed rod slidably mounted on said frame, and adapted to snap into locked engagement with the other locking member when the plate is fully depressed, and a push button mounted on the table and connected with said latch mechanism so that the same may be operated for 20 releasing said plate.

6. The combination with a table having a flat top with an opening within the margin thereof, of a game board to fit in and close 25 said opening and be flush with said top, a frame secured to said table beneath said top and surrounding said opening, a cross-bar secured to said frame, an upright post in the center of said frame and secured to said 30 cross-bar, a vertically deppressible plate slidably mounted on said post, means supporting said board above said plate, a spring surrounding said post between said plate and cross-bar for raising said plate and 35 carrying said board above said top, a latch mechanism for holding said plate depressed with said board flush with said top, said latch mechanism comprising two locking members, one in the form of a hook carried 40 by said plate and adapted to pass through a hole in said cross-bar when the plate is fully depressed, the other locking member being a spring pressed rod slidably mounted 45 on said cross-bar to snap into locked engage-

ment with said hook when the plate is depressed, and a push button mounted on the table and connected with said rod so that the latch mechanism may be operated for releasing said plate.

7. The combination with a table having a flat top with an opening within the margin thereof, of a game board to fit in and close said opening and be flush with said top, a frame secured to said table beneath said top and surrounding said opening, a vertically 50 deppressible plate slidably mounted in said frame, means pivotally supporting said board above said plate, a spring for raising said plate and carrying the board above said top, a latch mechanism for holding said plate depressed, a latch member carried by said plate and engaging said board when depressed for holding the same flush with said top, means for operating said latch mechanism for releasing said plate, and a 55 spring on said plate for swinging said board upward on its pivots when raised above said top by said plate.

8. The combination with a table having a flat top with an opening within the margin 60 thereof, of a game board to fit in and close said opening and be flush with said top, a frame secured to said table beneath said top and surrounding said opening, a vertically deppressible plate slidably mounted in said frame, upright arms secured to opposite sides of said plate, means for pivotally mounting said board between said arms, a latch mechanism for holding said plate depressed, means for operating said latch 65 mechanism for releasing said plate, a latch member mounted on said plate and adapted when the board and plate are depressed to engage said board and hold the same flush with said top, and a spring carried by said 70 plate and engaging said board to swing the same into open position above the top when said plate is raised.

In testimony that I claim the foregoing as my invention, I affix my signature, this 95 11th day of November, A. D. 1920.

PETER W. CHMIELOWSKI.
